(57) **CLAIM**

The ornamental design for a luminaire, as shown and described.

DESCRIPTION

FIG. 1 is a top perspective view of a luminaire showing a first embodiment of the new design;

FIG. 2 is a bottom perspective view of the luminaire of FIG. 1.

FIG. 3 is a right side elevation view of the luminaire of FIG. 1.

FIG. 4 is a left side elevation view of the luminaire of FIG. 1.

FIG. 5 is a front elevation view of the luminaire of FIG. 1.

FIG. 6 is a top plan view of the luminaire of FIG. 1.

FIG. 7 is a rear elevation view of the luminaire of FIG. 1.

FIG. 8 is a bottom plan view of the luminaire of FIG. 1.

FIG. 9 is a top perspective view of a luminaire showing a second embodiment of the new design;

FIG. 10 is a bottom perspective view of the luminaire of FIG. 9.

FIG. 11 is a right side elevation view of the luminaire of FIG. 9.

FIG. 12 is a left side elevation view of the luminaire of FIG. 9.

FIG. 13 is a front elevation view of the luminaire of FIG. 9.

FIG. 14 is a top plan view of the luminaire of FIG. 9.

FIG. 15 is a rear elevation view of the luminaire of FIG. 9; and,

FIG. 16 is a bottom plan view of the luminaire of FIG. 9.

Portions or features of the luminaire not shown in the drawings form no part of the claimed design. The broken lines in the drawings form no part of the claimed design.
